DESIGN FOR A DISPLAY STAND FOR PERFUME OR THE LIKE

Ted Mehrer, New York, N. Y., assignor to Abraham I. Gladstone, New York, N. Y.

Application September 5, 1940, Serial No. 94,810

Term of patent 7 years

To all whom it may concern:

Be it known that I, Ted Mehrer, a citizen of the United States of America, residing at New York, in the county of New York and State of New York, have invented a new, original, and ornamental Design for a Display Stand for Perfume or the like, of which the following is a specification, reference being had to the accompanying drawing, forming part thereof, and in which:

stand for perfume or the like, embodying my new design,

Figure 2 is a similar view taken at a ninety degree angle from the position of that shown in Figure 1, and

I claim:

The ornamental design for a display stand for perfume or the like, substantially as shown.

TED MEHRER.
